UNITED STATES PATENT OFFICE.

SPENCER R. LAWSHE, OF CHICAGO, ILLINOIS.

LIGHTNING-ROD AND COUPLING.

SPECIFICATION forming part of Letters Patent No. 400,464, dated April 2, 1889.

Application filed October 15, 1888. Serial No. 288,176. (No model.)

To all whom it may concern:

Be it known that I, SPENCER R. LAWSHE, a citizen of the United States, residing in the city of Chicago, county of Cook, and State of Illinois, have invented certain new and useful Improvements in Lightning-Rods and Lightning-Rod Couplings; and I do hereby declare the following to be a clear, full, and exact description thereof, reference being had to the accompanying drawings, and to the letters and figures of reference marked thereon, which form part of this specification.

My invention relates to lightning-rods which I put together in sections; and it consists in the method of fastening the coupling-burr to the several sections of the rod.

Figure 1 represents a portion of the spiral section of a lightning-rod having a tenon, A, at the end, with shoulders *b b*, which tenon I prefer making by cutting the section of the rod to the depth of the flanges a sufficient distance from the end to give the required length of tenon and turning each portion of the flange so cut upon itself, so as to form the shoulders *b b*, as shown in Fig. 2. Fig. 3 represents a coupling-burr having a male and female screw, the ends of which are provided with serrated flanges *C C*, having shoulders *d d*, as shown in a perspective view of the lower end of the

coupling. The end of the coupling is passed over the tenon A a sufficient distance, so that when the flanges *C C* are forced down against the rod the shoulders *d d* lock with the shoulders *b b* and form a perfect union, preventing the coupling from slipping or breaking from the rod. Fig. 4 represents a vertical section of the two parts of the coupling-burr joined and the flanges *C C* forced down against the rod, a portion of the flanges of the rod being broken away to show the shoulders *b b*, held in their position by the shoulders *d d* of the coupling-burr.

I do not confine myself to any particular form of rod or method of making the same. The rod may be composed of one material, or two or more, and of any form desired.

What I claim as my invention, and desire to secure by Letters Patent, is—

A coupling-burr provided at its ends with serrated flanges *C C*, having shoulders *d d*, which shoulders lock with the shoulders *b b* of the tenon A upon the flanges *C C* being forced down on the rod, all substantially as and for the purpose set forth.

SPENCER R. LAWSHE.
